UNITED STATES PATENT OFFICE.

JAMES M. FERGUSON, OF NEW ORLEANS, LOUISIANA.

BOILER-FLUE CLEANER.

SPECIFICATION forming part of Letters Patent No. 331,782, dated December 8, 1885.

Application filed February 4, 1885. Serial No. 154,918. (No model.)

To all whom it may concern:

Be it known that I, JAMES M. FERGUSON, of New Orleans, in the parish of Orleans and State of Louisiana, have invented a new and 5 Improved Boiler-Flue Cleaner, of which the following is a full, clear, and exact description.

The object of my invention is to provide a flue cleaner operating by a jet of steam for removal of dirt and soot from the flues, and to prevent formation of scale; and to these ends it consists in a jet-nozzle of novel construction, as hereinafter described and claimed.

Reference is to be had to the accompanying 15 drawings, forming part of this specification, in which similar letters of reference indicate corresponding parts in all the figures.

Figure 1 is a longitudinal section of my flue-cleaner. Fig. 2 is a view showing the manner of use with a horizontal boiler, and Fig. 20 3 shows the manner of use with a vertical boiler.

The nozzle A is secured upon the end of a tube-section, B, that is provided with a socket, 25 a, for a handle, and a neck at b for connection of a flexible pipe, by which the steam is supplied, as shown. The connection between the nozzle A and tube-section B is made by a pipe-section, B'; but the nozzle may be directly 30 connected to the tube-section B. For vertical boilers the tube will have a right-angle bend, as at i, Fig. 3, so that the nozzle can be properly inserted in the flue-tubes.

The general form of the nozzle A is that of 35 a truncated cone, the base or skirt portion c extending out to a width greater than the di-

ameter of the flues, so as to fit closely in the tube end and exclude air. The interior neck, d, is threaded for attachment to tube B, and at the outer end the neck is formed with a 40 disk, e, that closes the end of the cone, except that there is an annular space, I, between the cone and disk for escape of steam. There is also a central passage, f, in the disk.

The cleaner being inserted into the flue end, 45 and steam supplied by the flexible pipe h, as illustrated in Figs. 2 and 3, an unbroken current of steam is discharged against the sides of the tube, with the effect to sweep out all soot and other accumulations, thus thoroughly cleansing 50 the tube and preventing the formation of scale. The air is excluded by the close fitting of the nozzle in the tube, and a current of dry steam thus insured. The nozzle is durable, being cast in one piece, and with it the work 55 of cleaning flues can be easily and rapidly carried out.

Having thus described my invention, I claim as new and desire to secure by Letters Patent—

In a flue-cleaner, the nozzle having a central 60 aperture in its disk portion, said aperture having an inner tubular extension, around which is arranged an annular space, also opening through said disk portion, said tubular extension and annular space connecting with 65 a steam-chamber of the nozzle, all cast or made in one piece, substantially as and for the purpose set forth.

JAMES M. FERGUSON.
